UNITED STATES PATENT OFFICE.

DANIEL MCFARLAN MOORE, OF NEWARK, NEW JERSEY.

SICK-BED CHAIR.

SPECIFICATION forming part of Letters Patent No. 717,894, dated January 6, 1903.

Application filed April 18, 1902. Serial No. 103,498. (No model.)

To all whom it may concern:

Be it known that I, DANIEL MCFARLAN MOORE, a citizen of the United States, residing at Newark, in the county of Essex and State of New Jersey, have invented certain new and useful Improvements in Sick-Bed Chairs; and I do hereby declare the following to be a full, clear, and exact description of the invention, such as will enable others skilled in the art to which it apertains to make and use the same, reference being had to the accompanying drawings, and to numerals of reference marked thereon, which form a part of this specification.

15 This present invention has reference to a novel means or apparatus which for sake of description and illustration will hereinafter be termed a "sick-bed chair," the purpose of the invention being to provide a novel and 20 simply-constructed device or apparatus comprising a number of movable members or sections, whereby the apparatus can be placed in a flat condition in the bed directly along the side of a sick person who has been moved 25 upon his or her side, and then by turning or rolling the person directly upon the flat sections of the device and by proper manipulation of the said device bringing the body of the patient into a sitting posture, the body 30 of the patient at the same time being gently raised and elevated from the surface of the bed a sufficient distance to insert a bed-pan or other proper receptacle directly beneath the seat of the sick-bed chair to enable the 35 patient to attend to the necessary wants of nature.

The principal objects of the present invention, therefore, are, first, to provide an apparatus or device of the character and for the purpose 40 poses hereinafter more particularly set forth; secondly, to provide an apparatus or device made in folding sections, to have an apparatus or device of minimum thickness, which can be placed in a sick-bed alongside of the 45 patient, so as to enable the sick person to easily roll or be placed upon the apparatus without exertion; thirdly, to provide an apparatus or device the sections of which can be brought into such relative positions to 50 provide a chair the seat of which is sufficiently elevated above the surface of the bed that a pan or other receiving-receptacle can

be placed beneath the seat without having to lift the patient; fourthly, to provide a device or apparatus the movement of which gently 55 raises the patient and brings the patient into a natural sitting posture without any muscular effort whatever and in which position the bowels are more readily evacuated and with better results and the use of tedious and often 60 objectionable enemas are avoided, and, lastly, to provide a device or apparatus upon which the body of the patient is bent at the middle of the body when raised with the apparatus preparatory to the stool, whereby there will 65 be no straining of the other parts of the body or of the muscles; and the invention therefore is a great utility in confinement cases and such ailments where uremic poisoning is likely to occur, due mainly to careless handling of the person when lifting the patient or by the uncomfortable position of the patient when the ordinary bed-pan is placed beneath the partially-raised and strained body of the weak person and avoiding the 70 objectionable and strained positions in which a patient in confinement cases is usually placed by the orders of the best physicians, such as placing the patient upon the knees or placing a vessel in a sitting position upon 75 the mattress of the bed, and hence in an extremely unstable and dangerous position to a weak person to avoid the downward flow of the urine over the contiguous portions of the body and the possible uremic poisoning 80 that might otherwise take place.

With these various objects in view the invention consists, primarily, in the novel sick-bed chair hereinafter set forth; and, furthermore, my invention consists in the various novel arrangements and combinations of parts with a view of providing a simply-constructed and sanitary device or apparatus, all of which will be more particularly described in the following specification and 90 then finally embodied in the clauses of the claim.

The invention is clearly illustrated in the accompanying drawings, in which—

Figure 1 is a plan view of the sick-bed chair embodying the principles of my invention, the same being illustrated in the "flattened-out" relation of its parts, ready for placing the same in the position in the bed for

the reception of the body of the patient prior to the elevation of the latter to a sitting posture. Fig. 2 is a longitudinal vertical section of the same, said section being taken on line 2 2 in Fig. 1. Fig. 3 is a perspective view of the said device or apparatus with the several sections of the chair in their raised or elevated relation for bringing the patient into a sitting posture. Fig. 4 is a central vertical section of the device or apparatus when the said sections of the chair are in their raised or elevated positions. Fig. 5 is a detail plan of the hinged end portions of two of the sections of the device, illustrating one means of separable hinge connection for the taking apart of the sections for sanitary purposes; and Fig. 6 is a cross-section taken on line 5 5 in said Fig. 5.

Similar characters of reference are employed in all of the said above-described views to indicate corresponding parts.

Referring to the said drawings, the reference character 1 indicates the complete device or apparatus, the same consisting, essentially, of four members or sections 2, 3, 4, and 5, which are made of a light material, preferably papier-mâché, which can easily be kept clean and which can be easily molded and will not "strike cold" or chill the body 30 of the patient; but of course it will be understood that said members may be made of any other desirable material. These several sections, which are pivotally connected by means of suitable hinges 6, having their leaves suitably secured in countersunk portions along the edges of the respective sections, as shown, are made of any desirable widths and varying lengths, the two sections 3 and 5 being of about the same length and being connected 35 by the short or narrow member or section 4, while the member or section 2 is made quite long, all of which will be clearly evident from an inspection of Figs. 1, 2, 3, and 4 of the drawings. The said member or section 5 is 40 made with an opening 7 of the usual ovoid shape, as shown, and upon the inner surface of the member or section 2 there may be a bar or cleat 8. This bar or cleat serves one purpose of acting as a rail to guide a bed-pan 45 or other receiving vessel in its proper position directly beneath the previously-mentioned opening 7 when the members or sections of the device or apparatus have been brought into their raised or elevated positions. (Illustrated in Figs. 3 and 4 of the drawings.)

When the several sections or members of the device are in their flat relation to one another, as shown in Figs. 1 and 2, then the two members or sections 5 and 4 will rest directly above a portion of the long member 2 and above the member 3 in such a manner that the two members 5 and 4 will assume a slight angular relation to each other, as indicated in Fig. 2, 65 owing to the fact that the said bar or cleat 8 is of such thickness that the said section 5 rests upon the said bar or cleat 8, whereby

the two sections or members 5 and 4 can never be in a straight alinement. This is an essential feature to more readily enable the several sections or members to assume their relatively raised or elevated positions (indicated in said Figs. 3 and 4) when the section 2 is used as a lever and is moved in an upward direction of the arrow X. (Indicated in said Fig. 2 of the drawings.)

In order that the several members or sections 2, 3, 4, and 5 may be retained or raised in their elevated relation to provide the chair, having a receiving compartment 9, in which the bed-pan or other receptacle is to be placed, the device is provided with a suitable holding means, preferably in the form of stays or braces 10, which are pivotally connected with the member or section 3 by means of suitable 85 hinges 11 or any other suitable means and are provided at their free ends with hooks 12, arranged for separable holding engagement with suitably-constructed catch-plates 13 upon the section or member 2, all of which 90 will be clearly evident from an inspection of the several figures of the drawings.

To quickly and easily disconnect the several sections or members 2, 2, 4, and 5 for sanitary purposes and to thoroughly cleanse 95 all of the parts of the device or apparatus after use, the edges of the hinge-leaves at the respective edges of the several members or sections are connected by means of removably-arranged rods 14, each rod being made 100 with a suitable finger-piece 15, which can be arranged in suitably-placed depressions 16 at the edges of the adjacent sections or members, as illustrated in Fig. 5 of the drawings, so as not to interfere with closing or folding 105 of the several sections or members upon each other.

The hereinabove-described device or apparatus is used in the following manner: As soon as the patient desires to attend to the 110 necessary wants of nature the person is laid on his or her side and the closed or folded apparatus is placed in the bed directly alongside of the patient. The patient is then rolled directly upon the folded or closed apparatus 115 and gently arranged over the opening in the section or member 5. This having been done, the nurse takes hold of the free end of the section 2, moving it slowly in the direction of the arrow X in Fig. 2 of the drawings. 120 This movement brings the several sections or members in their relatively raised positions, (indicated in Figs. 3 and 4,) in which positions the parts are locked. At the same time the 125 protected body of the patient has been elevated above the surface of the bed in a sitting posture and at a sufficient distance to insert a proper receptacle in the compartment formed by the elevated sections or members of the apparatus. After the patient has attended to the necessary wants of nature the several sections of the device are again 130 brought into their closed or folded relation by the disengagement of the holding-stays

and the gentle lowering of the section 2. The patient thereupon is removed to one side of the folded device, and the latter is slipped from the bed.

5. From the hereinabove description of my invention it will be clearly evident that I have provided an efficient and useful sick-bed chair which is of great benefit in cases of sickness, where it is of great danger to the patient to be put to muscular exertion, and in the treatment of broken limbs, where it is extremely important that the patient shall be disturbed as little as possible and where a sitting posture of a person cannot be produced except 10 with muscular effort on the part of the patient, the use of the device or apparatus is of great benefit and comfort to the patient. I do not, however, limit myself to the use of the apparatus solely for the purpose of attending to the wants of nature, for the device may be readily used by the patient during convalescence in bringing the patient in a sitting posture in the bed, for other various purposes, as in the taking in of nourishment, 15 obviating the unsatisfactory use in bolstering up the patient with pillows.

I am aware that changes may be made in the general arrangements and combinations of the various parts without departing from 20 the scope of the present invention. Hence I do not limit my invention to the exact arrangements and combinations of the parts as described in the present specification and as 25 illustrated in the accompanying drawings, nor do I confine myself to the exact details of the construction of the said parts.

Having thus described my invention, what I claim is—

1. As a new article of manufacture, a sick-bed chair, comprising, a fixed, flat and solid board-like member and a number of collapsible, flat and solid board-like members, all adapted to be arranged in a folded and flattened-out relation so as to enable the folded 40 sections to be slipped beneath the body of a patient, and a means of pivotal connection between said fixed member and said collapsible members for bringing said collapsible members in their raised positions, substantially as and for the purposes set forth.

2. As a new article of manufacture, a sick-bed chair, comprising, a fixed, flat and solid board-like member and a number of collapsible, flat and solid board-like members, all adapted to be arranged in a folded and flattened-out relation so as to enable the folded 45 sections to be slipped beneath the body of a patient, and a means of pivotal connection between said fixed member and said collapsible members for bringing said collapsible members in their raised positions, and means connected with the said members for retaining them in their elevated positions a sufficient distance to enable the placing of a receiving vessel beneath the patient, substantially as and for the purposes set forth.

3. In a portable sick-bed chair, the combi-

nation, with a fixed, flat and solid board-like bottom member, and three other movable, flat and solid board-like members all connected 70 so as to be folded upon each other to be placed in bed under the body of the patient, said members being arranged and constructed that a movement of one of said members will raise the other two movable members above said 75 fixed member to provide a seat, substantially as and for the purposes set forth.

4. A portable sick-bed chair, comprising, a fixed, flat and solid board-like bottom member, and a series of collapsible and hinged, flat 80 and solid board-like members, all arranged 85 that a movement of said hinged members will elevate one of said members directly above said fixed member and will bring the body of a patient in a sitting posture, and means for retaining said hinged members in their elevated positions, substantially as and for the purposes set forth.

5. As a new article of manufacture, a sick-bed chair, comprising, a fixed, flat and solid 90 board-like member and a number of detachably-connected and collapsible, flat and solid board-like members, all adapted to be arranged in a folded and flattened-out relation so as to enable the folded sections to be 95 slipped beneath the body of the patient, and to be disconnected for cleaning after use, substantially as and for the purposes set forth.

6. As a new article of manufacture, a sick-bed chair, comprising, a fixed, flat and solid 100 board-like member and a number of detachably-connected and collapsible, flat and solid 105 board-like members, all adapted to be arranged in a folded and flattened-out relation so as to enable the folded sections to be slipped 110 beneath the body of the patient, and to be disconnected for cleaning after use, and means connected with the said members for retaining them in their elevated position, when in use, a sufficient distance to enable the placing 115 of a receiving vessel beneath the patient, substantially as and for the purposes set forth.

7. A sick-bed chair, comprising, a solid and flat bottom member, a back member movably 115 connected with the one edge of said bottom member, a short front member, movably connected with the opposite edge of said bottom member, and a seat member movably connected at its one edge with the upper edge of 120 the front member and at the opposite edge with said back member, substantially as and for the purposes set forth.

8. A sick-bed chair, comprising, a solid and flat bottom member, a back member movably 125 connected with the one edge of said bottom member, a short front member movably connected with the opposite edge of said bottom member, and a seat member movably connected at its one edge with the upper edge of 130 the front member and at the opposite edge with said back member, the said seat member being provided with an opening 7, substantially as and for the purposes set forth.

9. A sick-bed chair, comprising, a solid and flat bottom member, a back member movably connected with the one edge of said bottom member, a short front member movably connected with the opposite edge of said bottom member, a seat member movably connected at its one edge with the upper edge of said front member and at the opposite edge with said back member, and means arranged between the said bottom member and the said seat member to prevent the straight alinement of said members when folded, substantially as and for the purposes set forth.

10. A sick-bed chair, comprising, a solid and flat bottom member, a back member mov-

ably connected with the one edge of said bottom member, a front member movably connected with the opposite edge of said bottom member, a seat member movably connected at its one edge with the upper edge of said front member, and a means of separable connection between said members, substantially as and for the purposes set forth.

In testimony that I claim the invention set forth above I have hereunto set my hand this 15th day of April, 1902.

DANIEL MCFARLAN MOORE.
